ROOF OF LARGE SPAN

Henri Macelaine Pont, The Hague, Netherlands

Application July 8, 1947, Serial No. 759,584
In the Netherlands March 5, 1941Section 1, Public Law 690, August 8, 1946
Patent expires March 5, 1961

3 Claims. (Cl. 108—1)

1

The invention relates to a roof of large span and has for its object to provide a roof, which in comparison with known roofs is extraordinarily simple and cheap, has a light construction, can be heavily loaded and requires very few abutments.

According to the invention this object is attained by this, that the roof has an elastic structure balanced by tensioned connections and consisting merely of resiliently flexible curved rafters or rafter principals, which rest on corner abutments only meet in the top of the roof and are turned with their hollow sides to the inside, and of roofing networks interconnecting under tension said principals and a taut eaves-cable provided round about the roof on the level of the feet of the principals, said networks being situated in the roofing planes and composed of wires, tapes, cables or like completely flexible tightening means. Such a taut elastic roof, which, when dome-shaped, may be compared with an umbrella standing on the tips of its ribs only, has, as will be explained hereinafter, many advantages over rigid roofs, to which the known dome-structures also belong.

In a simple beam having a span l and supporting a specific load q , the greatest bending moment is $\frac{1}{8} ql^2$. This moment must be taken up by the cross-section of the beam. Consequently, the beam must have a neutral zone, above which compressive stresses and below which tensile stresses are produced in said beam. Although in the neutral zone the stresses are reduced to nothing, the material in that zone cannot be spared, since it is required for the interconnection of the upper and the lower fibers of the beam. In framed beams certain members are provided for this connection. The result of these facts is, that the specific weight of a rigid beam increases with about the square of the span l .

In a completely flexible wire, cable or the like suspending from two points there is, when loaded, no moment, but tensile stresses are produced only. There is no neutral zone. The cross-section of the wire is loaded uniformly, that means as efficient as possible. If the load is equally divided over the length of the wire, the latter will hang in the curve of a catenary and in the connecting points of the wire a maximum tensile force R will be produced, which is given by

$$R = \frac{1}{2 \sin \alpha} ql$$

2

Herein α is the angle between the tangent to the wire in said points and the horizontal plane. Thus the specific weight of the tightened structure is directly proportional to the span.

5 For short spans, for which $\frac{1}{8} l$ will generally be less than

$$\frac{1}{2 \sin \alpha}$$

10 a taut structure is not very appropriate to the purpose. When, however, the span increases, the last mentioned construction will be more favourable and for large spans an enormous gain of weight and material is made with said construction.

15 The disadvantage of a structure suspended under tension from columns, that in the connecting points horizontal forces equal to

$$\frac{1}{2 t g \alpha} ql$$

20 are produced, which forces would increase the danger of buckling of the columns, does not exist in the construction according to the invention, since it has rafter principals which are bent towards the top. These horizontal forces set up in the curved principals only resultants, which lie in the meridian planes of those principals, are directed inwards and thus prevent the principals from bending further to the outside. Owing to their curved shape the rafter principals cannot buckle inwards. If sufficiently close networks are used, so that the principals are tied between the roofing planes along their entire length, the principals cannot buckle to the left or to the right either.

25 The construction must be protected from torsion. This can be obtained by a suitable manner of weaving the network of the roofing planes between the rafter principals or by providing bracings in said roofing planes. Said bracings can best be placed under the network of the roofing planes. In that case they can also take up part of the weight of the roof covering.

30 Another advantage of the construction according to the invention is, that the network of the roofing planes, which obviously in the first place serves for the tightening of the structure, can be used directly for the support of the roof covering. In the known rigid roof-constructions the purlins and the roof-joint-grids actually form a dead weight, since they are not an essential part of the supporting structure. They only serve for carrying the weight of the roof covering to the roof principals.

If the eaves-cable and the rafter principals are interconnected by rafter-wires and anti-torsion-bracings walls or doors can be suspended from the eaves-cable for closing the roofed space, without reinforcement of the construction being necessary.

The roof, which is flexible and taut in all its parts, has the further important advantage, that, when loaded on one side, it regains its internal equilibrium automatically by deformation. If, for instance, one of the roofing planes is heavier loaded by strong wind pressure or dust snow than the other roofing planes, the network of the heavier loaded side deflects a bit more, whereas the other roofing planes are tightened somewhat more. The rafter principals extending along the extra loaded roofing plane are pulled to one another a bit, so that the purlin-wires of the network in that plane are eased off, whereas these wires in the other roofing planes are more tightened. The same applies to the rafter-wires of the network. The result thereof is, that the whole top of the roof is moved in the direction of the most loaded side; consequently, in the case of heavy wind pressure, moves against the wind. A small shortening of the span between two rafter principals causes a considerable increase of the sag of the roof network. On the contrary a slight increase of the span causes a considerable decrease of the sag. From the formula

$$R = \frac{1}{2 \sin \alpha} ql$$

it appears, that in the extra loaded roofing plane the stresses increase by the increase of q , but decrease by the increase of the sag-angle α , whereas in the remaining roofing planes, in which planes q does not vary, the stresses increase by the decrease of the sag-angle α . It appears that, depending on the shape of the roof, the stresses in the various planes (which stresses will, of course, balance each other) will not increase more than 25-30% when the load on one of the planes is doubled. All stresses in the flexible roof are controllable. Therefore the factor of safety may be chosen low.

On the contrary in a rigid construction the stresses in the parts of the roof, the load on which is doubled, are twice as heavy in those parts, whereas in the parts not being extra loaded uncontrollable stresses are produced. In this case a high factor of safety, which means a heavy construction, is necessary.

In a roof according to the invention compressive stresses are found only in the rafter principals and tensile stresses occur only in the networks. The rafter principals must be resilient and massive as much as possible. Hollow constructions and frame work are less suitable for these members. Abutments are only required at the corners of the polygon roof. According to the invention the abutments may be constructed in such a manner, that they have a tightening action on the roof. This is obtained, when the feet of the rafter principals rest on abutments, each of which consists of posts sloping inwards from the bearing surface of the involved principal and of a vertical tie between the joint of said posts and a ground anchorage.

For the elucidation of the invention reference is had to the drawing which illustrates in diagram a square roof according to the invention; in the drawing:

Fig. 1 is a plan view of the roof,

Fig. 2 is a sectional view on the line II-II in Fig. 1.

Fig. 3 is a plan view of the roof under wind load,

5 Fig. 4 is a sectional view on the line IV-IV in Fig. 3, and

Fig. 5 is a perspective view of a roof seen in a slanting direction from above.

In the drawing 1 designates a number of resiliently flexible curved rafters or rafter principals meeting in a top 2. In the roofing planes networks of, for instance, steel wire or cable are connected under tension between said principals. These networks consist of purlin-wires 3, rafter-wires 4 and anti-torsion bracings 5. The nearly horizontal lower wire 6 is the eaves-cable. It appears from Fig. 2 that due to the sag of the network the middlemost rafter-wires have a flat S-shape. The anti-torsion bracings 5 extend from the rafter principals to the eaves-cable 6. Although in the drawing a network having relatively coarse meshes is shown, actually it can be easily made so, that it is adapted to support the roof covering, for instance tiles, directly.

25 The rafter principals 1 rest on abutments, each of which consists of two posts 7, which slope inwards from the joint 8 and enclose an angle. These posts are pressed outwards by the weight of the roof, so that a tightening action is exerted on the roof on the base thereof. In order to prevent the whole from tilting the joints 8 are connected to an earth-anchorage 10 by a tie 9.

30 It appears from Figs. 3 and 4, that the sag of the extra loaded roofing plane increases and that of the other roofing planes decreases, when the roof is extra loaded on one side, for instance by the wind (see arrow 11). In that case the top 2 is displaced against the wind till the equilibrium between the forces acting on the principals is restored. In Figs. 3 and 4 the full lines show the construction, when an extra load is exerted on one side, whereas the situation is shown in dotted lines when the load is uniformly divided. Thereby it can be clearly seen, how the rafter principals, the purlin-wires and the rafter-wires are deformed during an on-sided load.

35 If it is required to close the roof on the sides, the necessary walls, doors or flaps can be suspended from the eaves-cable 6.

40 Roofs of the described kind are suitable for very large spans, varying for instance from several tens to several hundreds of meters.

45 What I claim is:

1. A roof of large span comprising, in combination, abutment structures at the corners of the roofed space only, resiliently flexible curved rafters, which rest on said abutment structures, meet in the top of the roof and are turned with their concave sides toward the inside, eaves-cables provided round about the roof on the level of the lower ends of said rafters, networks composed of completely flexible stretchable wire-like means provided in the roofing planes between said rafters and said eaves-cables and keeping the latter bent upwards, and a roof covering supported directly by said roofing networks, said rafters, said eaves-cables and said roofing networks constituting a balanced elastic umbrella-like structure standing on the tips of its ribs only.

2. A roof according to claim 1, in which the abutment structures are adapted to move in the meridian planes of the rafters and to force the lower ends of said rafters to the outside by the weight of the roof.

3. A roof according to claim 1, in which the abutment structures each consists of pivotally supported posts jointed at their upper ends and sloping inwards from said upper ends, a resilient tie and an earth-anchorage, said tie interconnecting the jointed upper ends of said posts and said earth-anchorage, and the rafters resting on and being hinged to the jointed upper ends of the posts of the abutment structures.
